UNITED STATES PATENT OFFICE.

EDWARD S. J. PHILLIPS, OF NEW YORK, N. Y.

FENDER FOR SHIPS' PIERS.

1,210,832.

Specification of Letters Patent.

Patented Jan. 2, 1917.

Application filed June 22, 1916. Serial No. 105,105.

To all whom it may concern:

Be it known that I, EDWARD S. J. PHILLIPS, a citizen of the United States, residing in the borough of Manhattan of the city of New York, in the State of New York, have invented certain new and useful Improvements in Fenders for Ships' Piers, of which the following is a specification, reference being had to the accompanying drawings, forming a part hereof.

This invention relates to fenders intended to be interposed between the broad side of a ship and its pier and has for its principal object to provide a fender which shall neutralize to the greatest extent possible, the effects of tides and currents such as tend to force the broad side of the ship toward the pier and hold it there. As is well known, the strength of such tides and currents at times becomes so great that the ship is forced against the side of its pier or against an interposed fender so firmly as to make it practically impossible to move the ship in either direction or, at least, to involve great danger to both the ship and pier by such relative movement. Again, it has been found that fenders of known type are unsatisfactory under many prevailing conditions because of their tendency to follow the movements of the ship and thereby, oftentimes, be moved out of engagement with the pier. This fault is especially serious when a ship is leaving the pier and particularly when it is being warped around the end thereof. Obviously, when swinging, it is desirable that a fender should be maintained at all times in position between the ship and the pier adjacent the end thereof and yet follow the movements of the ship sufficiently to lie in snug engagement with the broad side of the ship throughout its length and swing about the end of the pier with the ship.

In accordance with the present invention there is provided a fender which shall overcome the disadvantages of known fenders as pointed out above and satisfy all requirements of use and be especially effective under adverse conditions such as are created by tides and currents for the purpose of shielding the ship from the pier at all times without permitting it to assume such a position with respect to the pier as to be pressed laterally toward the same by the tide or current.

A further object of the invention is to provide a fender which shall be of such form

as to lie constantly in engagement with the broad side of the ship and with the dock and yet permit free movement of the ship with relation thereto without partaking of such movement to an extent sufficient to move it away from the pier.

The invention has been illustrated herein as embodied in two different forms of fenders and it may be found that one of these forms is especially adaptable for use where the ship is to be swung about the end of the pier, either when entering or leaving. In this form of fender provision is made for maintaining it at the end of the pier and in such relation to the ship as to permit it to swing about the end with the ship.

The invention will be described in greater detail in connection with the illustrated embodiments in the drawings, in which—

Figure 1 is a view in plan of a fender embodying the invention and intended to be especially suitable for use adjacent the end of the pier. Fig. 2 is a view in side elevation of the fender shown in Fig. 1. Fig. 3 is a view in end elevation of the fender shown in Figs. 1 and 2. Fig. 4 is a view in plan of a somewhat modified form of fender. Fig. 5 is a view in side elevation thereof. Fig. 6 is a view in end elevation of the fender shown in Figs. 4 and 5. Fig. 7 is a view indicating, somewhat conventionally, the manner in which the fender shown in Figs. 1-3 is employed most effectively. Fig. 8 is a view similar generally to Fig. 7 but showing the interposition of the fender illustrated in Figs. 4-6 between a ship and its pier.

The fender *a* shown in Figs. 1-3 is formed with a straight edge *a'* along one side thereof and with two oppositely inclined faces *a''* along the other side thereof, these inclined faces extending inwardly toward the mid-section of the fender but preferably terminating in a short straight-edge section *a'''* which may be disposed at about this mid-section. The fender as described is intended to float in the water alongside the ship with its straight edge *a'* in engagement with the ship's side and the other edge in engagement with the pier. In practice the fender *a* will generally be secured loosely to the pier, as by a rope or the like engaged with one or more of the lugs *a''* carried with the fender.

Referring now to Fig. 7, the manner of using the fender described in the most effec-

tive way and the principle of operation by which it serves to afford the desired degree of protection to the ship and pier without interfering with the ship's movements, will 5 be described. In this figure the outline of the broad side of a ship is indicated by the dotted line *b* while the side *c* and end *d* of its pier have been shown conventionally by a full line. Adjacent the end of the pier 10 there has been disposed the improved fender *a* with its straight-edge mid-section *a*³ on its outer side resting about opposite the corner of the pier. At this time, one of the inclined sections *a*² will rest snugly against the 15 side *c* of the pier, so that the ship will be maintained at an angle with relation to the pier and the force of a lateral current or tide indicated as applied to the ship along the line of the arrow *e* will necessarily have a 20 longitudinal component tending to move the ship from its slip, the general direction of this resultant being indicated by the other arrow *f*. If the two sides of the fender *a* were parallel, as in known structures, 25 the force of the tide would impress only a lateral thrust on the straight edges of the fender between both the broad side of the ship and the side of the pier, thereby creating such a pressure between these contacting 30 surfaces as would tend to resist to an undesirable degree relative movement as between the ship and the fender or the ship and the pier. The longitudinal component of force secured from the lateral thrust of 35 the tide on the inclined face of the wedge shaped fender serves to assist the ship in its relative movement with relation to the fender. Assuming that the ship is leaving its pier, it will be seen from Fig. 7 that it has 40 reached a position at about where it may commence to swing about the end *d* of the pier. Such swinging would necessarily be accompanied by a swinging of the wedge *a* about the corner of the pier, the straight 45 edge *a'* of the fender remaining in snug engagement with the broad side of the ship throughout the length of the fender. The swinging of the fender around the corner of the pier will occur usually along an axis 50 adjacent the straight edge portion *a*³ of the fender, the tangential engagement of the pier surface with the side of the fender at all times insuring a free swinging movement of the ship. Eventually, it will be 55 evident that the other inclined surface *a*² of the outer side of the fender *a* will move into engagement with the end *d* of the pier at which time the ship will lie in a position nearly at right angle to its normal position 60 in the slip. During the swinging, the engagement of the inclined surfaces of the fender with the outline of the pier and the relative arrangement of these inclined faces with relation to the straight edge section *a*³ 65 will all serve to permit free movement of the

ship with the fender without tending, however, to move the fender out of engagement with the pier. This condition is one of the prime considerations in the use of a fender under the conditions described.

The form of fender *g* shown in Figs. 4-6 embodies many of the advantages described with relation to the first named embodiment, but is of such character as to be particularly useful when the ship is alongside the pier and either entering or leaving its slip by direct movement rather than a swinging movement such as was before assumed. The fender *g* is formed as a simple wedge having oppositely inclined straight edges, one of which will rest throughout in engagement with the broad side of the ship and the other of which will engage the width of the pier. This fender, like the fender *a*, may be anchored against movement by means of securing devices engaged with eyes *h* carried thereon, but the fender is not intended to have any positive support, but to float on the surface of the water between the ship and the pier.

When the fender *g* is in its intended position between the ship *b* and pier *c*, as indicated in Fig. 8, with the tide pressing the ship laterally against one of the inclined edges of the fender, as suggested by the direction of the arrow *e*, the thrust of this tide may be resolved into two components, one of which acts normal to the inclined face of the fender, and the other of which acts substantially parallel thereto. This last named component tends to move the ship along the inclined edge of the fender so that when the ship is being propelled from its slip the tide will serve as a positive help to such movement rather than as a positive hindrance thereto, as heretofore. This moving force of the tide as applied to the ship in the manner described, it is to be noted, cannot move the fender with the ship since the wedge shape of the fender tends to hold it snugly between the side *c* of the pier and the ship and thereby positively prevent its movement toward the end *d* of the pier. In previous constructions where the opposite sides of the fender have been parallel, movement of the ship from its slip has always tended to cause corresponding movement of the fender therewith with the result that the fender has eventually been carried beyond the end of the pier and thereby rendered useless. It is to be understood that when the ship is entering its slip, the wedge fender may be applied with equal advantage to neutralize the effect of the lateral thrust on the ship of the tide by reversing the position of the fender so that the longitudinal component of force of the tide along the edge of the fender will tend to move the ship in the desired direction.

From the description given of the form

of the fender *g* shown in Figs. 4-6, it will appear that the first described embodiment *a* shown in Figs. 1-3 partakes of the character of the fender *g* by the duplication of the inclined surfaces along one edge. The principle of operation involved when the fenders are in use is substantially the same except that the double surfaced fender *a* is specially suitable for use at the corner 10 of a pier for the reason that its form insures its retention in position at the corner during the swinging movement of the ship.

In the appended claims the invention is set forth in such manner as to make it clear 15 that it is not to be limited to only one or the other of the embodiments shown, but, indeed, is of such scope as to embrace both these and modified forms intended to accomplish the same purpose in substantially 20 the same manner.

I claim as my invention:

1. A fender for ships' piers having relatively inclined side faces.

Copies of this patent may be obtained for five cents each, by addressing the "Commissioner of Patents, Washington, D. C."

2. A fender for ships' piers having relatively inclined side faces and means to secure the fender to the pier. 25

3. A fender for ships' piers adapted to float between the broad side of a ship and the pier and having a substantially wedge shaped horizontal cross section. 30

4. A fender for ships' piers having a straight edge to engage the broad side of the ship and oppositely inclined faces formed on the other edge. 35

5. A fender for ships' piers having a straight edge to engage the broad side of the ship, inwardly extending and oppositely inclined faces formed on the other edge and a straight edge section on the second named edge of the fender substantially parallel to the first named edge and at which the oppositely inclined faces terminate. 40

This specification signed this 20th day of June, 1916.

EDWARD S. J. PHILLIPS.
